[57] **CLAIM**

The ornamental design for a gaming device with speakers, as shown and described.

DESCRIPTION

FIG. 1 is a perspective view of a gaming device with speakers, showing our new design;

FIG. 2 is a left side elevational view thereof;

FIG. 3 is a front elevational view thereof;

FIG. 4 is a right side elevational view thereof;

FIG. 5 is a top plan view thereof; and,

FIG. 6 is a rear elevational view thereof.

The bottom surface is substantially plain and unornamented. Broken line illustration in the drawing disclosure is not part of the design sought to be patented in the present application.
